UNITED STATES PATENT OFFICE.

ADOLPH H. COHN, OF NEW YORK, N. Y.

HOSE-SUPPORTER.

SPECIFICATION forming part of Letters Patent No. 746,677, dated December 15, 1903.

Application filed July 3, 1903. Serial No. 164,106. (No model.)

To all whom it may concern:

Be it known that I, ADOLPH H. COHN, of the city of New York, borough of Manhattan, in the county and State of New York, have 5 invented a new and Improved Hose-Supporter, of which the following is a full, clear, and exact description.

My invention relates to hose-supporters; and it consists of certain novel parts and combination of parts, particularly pointed out in the claims concluding this specification.

In the accompanying drawings, Figure 1 shows a hose-supporter involving my invention. Figs. 2, 3, and 4 are modifications 15 thereof. Fig. 5 shows the application of the device illustrated in Fig. 1.

The following is a description of the construction shown in the drawings, which illustrate my invention in the forms in which I at 20 present prefer to embody it; but it will be understood that various modifications and changes may be made in details without departing from the invention and without exceeding the scope of the concluding claims.

Reference being had to Fig. 1, A A are 25 tapes, preferably composed of elastic material and made adjustable in length by means of the slides B B. At one end of each tape are secured the cords D D, to which are attached the fasteners E E. These fasteners 30 may be of any suitable type, of which several are now well known and three different forms of which are shown in Figs. 1, 2, and 3, respectively. To the other end of each 35 tape A are secured the hooks C, to which the cord D of the other tape may be fastened.

The modification shown in Fig. 2 differs 40 from that described in Fig. 1 only in the fact that the hooks C C are made adjustable on the tapes by means of the slide F F, forming part of the hooks.

Fig. 3 illustrates a modification in which A' A' are the tapes, adjustable by means of the slides B' B'. C' C' are loops secured to 45 the tapes at one end. E' E' are the fasteners attached to the other end of the tapes. Upon the tapes are adjustable slides F' F', affixed to which are the studs G G. These studs engage with the loops C' C'.

50 In Fig. 4, A² A³ designate the tapes; B² B³, the means for adjusting them. At one end each of these tapes is secured to the ring H. The

tape A² has secured to its other end the ring H', while the tape A³ has secured to its other end the hook C². The fasteners E² E³ are attached to the rings H and H'. 55

I will now describe the method of applying my invention with its several modifications.

The devices shown in Figs. 1 and 2 being in two parts, the cord D of one part may be 60 first attached to the hook C of the other part. The device may then be placed about the leg and the other cord D attached to the other hook C. The entire device may be then adjusted to the desired size by means of the 65 slides B B and, in Fig. 2, also by means of the slides F F. The fasteners E E are then secured to the hose.

In the device of Fig. 3 there are also two parts. The loop C of one part may be first 70 attached to the stud G of the other. The device may then be placed about the leg and the other loop and stud secured together. The whole device may then be adjusted to the desired size by means of the slides B' B' 75 and F' F'. It may then be fastened to the hose by means of the fasteners E' E'.

The device of Fig. 4 is placed about the leg, and the hook C² is attached to the ring H'. The hose are then secured to the fasteners E² E³. 80

Having thus fully described my invention, what I claim, and desire to secure by Letters Patent, is—

1. In a hose-supporter the combination of 85 a plurality of detachable tapes having hose-supporting clasps attached to each of said tapes.

2. In a hose-supporter the combination of 90 a plurality of detachable elastic tapes with hose-supporting clasps attached to each of said tapes.

3. In a hose-supporter the combination of 95 a plurality of detachable tapes with hose-supporting clasps attached to each of said tapes and means for attaching said tapes together.

4. In a hose-supporter the combination of 100 a plurality of tapes having hose-supporting clasps attached to each of said tapes, means for adjusting said tapes and means for detachably securing said tapes together.

5. In a hose-supporter the combination of 105 a plurality of adjustable tapes, a plurality of

- hose-supporting clasps attached thereto and detachable means for attaching said tapes together.
6. In combination in a hose-supporter, a plurality of tapes, each tape having a hose-supporting clasp attached thereto, and means for detachably securing said tapes together.
7. In combination in a hose-supporter a plurality of tapes, each tape being adjustable and having a hose-supporting clasp attached thereto and detachable means for attaching said tapes together.
8. In combination in a hose-supporter a plurality of adjustable elastic tapes, each tape having a hose-supporting clasp attached thereto and means for detachably securing either tape to the other.

9. In a hose-supporter the combination of a plurality of tapes, each tape having hose-supporting clasps attached thereto, and means connected with each tape for detachably securing it to the other.

10. In a hose-supporter the combination of a plurality of adjustable tapes, each tape having hose-supporting clasps attached thereto, each tape being provided with a device for securing it to the other tape.

In testimony whereof I have hereunto signed my name in the presence of two subscribing witnesses.

ADOLPH H. COHN.
